UNITED STATES PATENT OFFICE.

CHANT A. MILLER, OF ST. LOUIS, AND ROYAL V. MILLER, OF ST. JOSEPH, MISSOURI.

VENTILATING DEVICE.

1,104,816.

Specification of Letters Patent. Patented July 28, 1914.

Application filed December 22, 1913. Serial No. 808,204.

To all whom it may concern:

Be it known that we, CHANT A. MILLER and ROYAL V. MILLER, citizens of the United States, residents, respectively, of St. Louis, 5 State of Missouri, and St. Joseph, in the county of Buchanan and State of Missouri, have invented a new and useful Ventilating Device, of which the following is a specification.

10 Our invention is a simple, substantial, durable and inexpensive ventilating device used in supplying fresh air and separately removing foul air from sleeping car berths, cars, vehicles, rooms, and the like at one and 15 the same time, and the objects of our invention are to so construct a device of this class, that cinders, snow, rain, sleet and the like, will not be admitted, therethrough, nor 20 cough and cold producing drafts allowed to enter the apartment served thereby, and that dust particles will be caused to settle in 25 the air admitting passage and chamber.

Further objects are, to so arrange and construct the parts of a ventilator, that the same 30 may be applied as a detachably attached device, or be built in with the body of an apartment, as a fixture, and also to so construct a 35 ventilator, that the windward end portion of the same will be warmed by the outgoing air, for preventing the accumulation of frozen 40 moisture on the end and in outside passages; thereby keeping the same open.

Other objects are to so construct a ventilator that the same will offer the minimum 45 amount of resistance to the wind and maintain the maximum amount of efficiency.

We attain these objects by the mechanism 50 illustrated in the accompanying drawing, in which:—

Figure 1 is a perspective view of the ventilator, showing the inner side, the top and one end of the same. Fig. 2 is a perspective view of the ventilator, with the outer wall removed for exposing the outer air passages 55 and ports. Fig. 3 is a perspective view of the ventilator, in the same position as seen in Fig. 1, with the inner side and top removed to avoid obscuring the internal parts. Fig. 4 is an end view, in perspective, of the ventilator, looking toward the right. Fig. 5 is a perspective view of the outer side, top, and one end of the ventilator, as it appears when in use, in an ordinary car window. Fig. 6 is a view similar to Fig. 5, but showing the 60 ventilator in use in car roof windows.

Referring to Figs. 2 and 3, the outer wall G, vertical partition M, top E, horizontal partition K and bottom H, form the boundaries of the outer air passages A and B which are open at both ends. The end portions of partition M are so deflected that the ends of said outer passages are gradually widened toward their extremities, thus presenting greater area to the outer atmosphere for forcing a greater volume of air there- 65 through.

Referring to Figs. 2, 3 and 4, port C is cut through partition M, at such point on said partition, that a small part of one of said inclined portions and a small part of the adjacent uninclined portion of said partition are thereby removed; which causes the outer edge of said port to be farther than the inner edge of same, from outer wall G. Connected with partition M, at the inner edge 70 of port C, is the tongue R, extending inward therefrom, parallel with said inclined end portion of partition M. Baffle plate O has its left end portion curved around the free vertical edge of tongue R, at a distance 75 therefrom similar to the distance between the latter and the said inclined portion of partition M, the left edge of said curved portion is connected with said inclined portion of partition M, while the remaining and flat 80 portion of said baffle plate extends toward the right, at a slightly increasing distance from said tongue, and terminates at a distance from partition M, forming communication, therebetween for inner air chamber 85 U, and the return bend air duct W, which latter is thus formed around the sides and free end of tongue R, and communicates with passage A, through port C. Said inner air chamber U is seen between the right portion 90 of baffle plate O and the deflector L, which chamber rapidly increases in width toward its outer edge, and opens into said ventilated compartment, not shown. Deflector N, partition M, tongue S and baffle plate P, are 95 similarly constructed but arranged reversely to the described parts, for forming air chamber V and the return bent air duct T, one end of which communicates with passage B, through port D, (see Fig. 2). Said port D 100 is formed in the same manner as the previously described port C inasmuch as that its outer edge is farther than its inner edge, from outer wall G. These ports are thus 105 formed for influencing the forcing and ex- 110

hausting of air, through ducts W and T, as hereinafter fully described. Drain opening X is formed through partition M and affords a small communication between duct W and 5 passage B. The inner or front edges of deflectors diverge from each other, forming void Q between them.

Referring to Figs. 1 and 4, the inclined plates I and I' form the upper and lower 10 boundaries respectively of the open sides of inner air chambers U and V. Plate I has the vertical flange I'' formed on its free edge and is adapted to have the lower edge of an ordinary car window sash (not 15 shown) lowered thereon, with flange I'' extending upward against the inner surface of the lower edge portion of said sash, for detachably holding the described ventilator in place and for providing a weather proof 20 joint at the bottom of said sash. Legs J J are adapted to rest upon the outer portion of the sill of said window, while the lower inclined plate I' is adapted to rest upon the inner portion of said sill, for supporting 25 said ventilator, and for providing a weather proof joint between said sill and the bottom of said ventilator.

Referring to Fig. 3, in operation, while 30 the described ventilator is being carried toward the left, the same causes a draft of air to pass toward the right through passage A, and in like manner causes air to similarly pass through passage B. The speed of said 35 drafts is increased when the same reaches and passes through the central, narrowed portions of said passages. Since duct W is inclined toward the same direction that 40 said draft of air is passing through passage A, it is evident that the same causes air to be exhausted from said duct through port C and into passage A. Since inner air chamber U, and duct W, form an exhaust conduit, which gradually decreases in width until 45 port C is reached, and since said port is but one half the height of said conduit, it is evident that the current of air exhausted therethrough will be slow of speed and distributed over a considerable area where the same enters air chamber U, thus providing 50 an exhaust for foul air from said apartment, without producing sever draft. It will be understood that the air exhausted from said apartment is warmed, and since the same is exhausted through duct W past 55 the inclined end portion of partition M that said portion is thereby warmed and that said warmth is transmitted therefrom to other parts of the left end of passages A and B, thereby preventing accumulation of 60 frozen moisture thereon. Should an appreciable amount of water caused by rain, enter passage A and gravitate from horizontal partition K, through port C onto bottom H, the same would be exhausted therefrom 65 through drain opening X into, passage, B,

and ejected therefrom, into the open air, by the previously described draft of air there-through. While the described exhausting of air from said apartment is taking place, the draft of air through passage B is being forced past port D (see Fig. 2,) and expands upon reaching the same. A part of 70 said air is deflected into and through said port by the adjacent deflected portion of partition M. The thus deflected air is 75 forced through duct T and inner air chamber V which form a conduit of increasing width which causes the thus supplied fresh air to move slowly from chamber V into said apartment, without producing sudden or severe drafts. It will be readily understood, that this slow and tortuous movement of air, causes dust particles to settle 80 therefrom, in said duct and chamber, onto bottom H.

It will be seen in Fig. 2 that the outer edge of port D is out of alinement with the uninclined central portion of partition M, as previously described, and it will be understood that the inertia of heavy particles 90 of matter, such as cinders, snow flakes, and the like prevents the same from being deflected from their straight course through passage B and thereby prevents the same from being deflected into and through said port, and into said apartment, but are carried out at the right end of said passage; thus forming what might be termed air-blast 95 separating means by which heavier particles of matter are separated from the air admitted into the served apartment. 100

Since all of the parts to left of void Q, (see Fig. 3,) are the same in construction and operation, as the parts at the right of said void, except that the same are reversely inclined to air passages A and B, it is evident that the described operation of the 105 ventilator is reversed while the same is moved toward the right.

It will be seen in Fig. 2, that the separate 110 air passages A and B, with their respective ports C and D, provide fresh air inlet means and foul air outlet means that are at all times separated; thus preventing the return into said apartment of any part of the exhausted foul air, and insuring an inflow of 115 pure, fresh air, through the described ventilator.

While we have shown and described our 120 ventilator in the foregoing manner, with an air exhaust port and an air supply port shielded from direct action of the elements, and with specifically shown and described air ducts leading from said ports, it is evident that said ports and ducts could be arranged in a variety of ways, and be so proportioned and arranged as to adapt the same 125 to be used in various situations, without departing from the spirit of our invention all of which we reserve the right to do. 130

Having fully described our invention what we claim as new and desire to secure by Letters Patent is:—

1. In a ventilator adapted to ventilate sleeping car berths, cars, vehicles, rooms and the like, an upper horizontally disposed outer air passage having open ends; a similar lower outer air passage directly beneath said upper passage; an inner air chamber for said upper passage said chamber having an open side opening into said ventilated apartment; an air duct whereby said upper passage and said air chamber are connected said duct being inclined toward the center 15 of said upper passage at its juncture therewith; another air chamber having an open side opening into said ventilated apartment; and another air duct whereby said lower passage is connected with said other air chamber said other duct being inclined toward the center of said lower passage at its juncture therewith.

2. In a ventilator adapted to ventilate sleeping car berths, cars, vehicles, rooms and the like, an upper outer air passage horizontally disposed and having flared open ends; a similar lower outer air passage directly beneath said upper passage; an inner air chamber for said upper air passage said 30 chamber having a flaring open side opening into said ventilating apartment; an air duct whereby said upper air passage and said chamber are connected said duct being inclined toward the central portion of said upper passage at its juncture therewith said duct and chamber together forming an S shaped air conduit the transverse area of which increases from said juncture to said apartment; another similarly formed inner 35 air chamber; and another air duct whereby said lower air passage is connected with said other air chamber said other duct being reversely inclined to the inclination of the first mentioned duct at its juncture with said lower passage.

3. In a device of the character described, an upper air passage having open ends; a similarly formed lower air passage beneath said upper air passage said air passages being adapted to have air pass and reversely pass therethrough; air conducting means connected with said upper passage said conducting means being adapted to conduct air exhaust from an apartment while air is 50 passed through said upper passage and to conduct air into said apartment while air is reversely passed through said upper passage; other air conducting means connected with said lower passage said other conducting means being adapted to conduct air therefrom into said apartment while the air is being exhausted through the first mentioned conducting means and to exhaust air 55 from said apartment through said lower passage while air is being admitted through

said first mentioned conducting means, the conducting means for both of said passages being so positioned that while air is being exhausted through either one of said conducting means that said exhausted air passes 70 alongside of and against the air inlet end portion of both said upper and lower passages for warming the same.

4. In a ventilator, an outer air passage having both ends open and being adapted to have air pass and reversely pass therethrough; a port formed through one side of said passage; an inner air chamber having a flaring open side adapted to open into an apartment; a return bent air duct having one of its end portions inclined toward the central portion of said passage and connected therewith through said port and its other end opening into said chamber said duct being of greater transverse area at its ported end than the area of said port and together with said chamber forming tortuous air conducting means the transverse area of which increases from the ported end thereof to and including the flaring open side of said chamber.

5. A ventilator adapted to ventilate sleeping car berths, cars, vehicles, rooms and the like, comprising a vertical outer back wall; a top; a bottom; a horizontal partition and a vertical partition forming two outer horizontal passages for passage of air therethrough, one passage being above the other, said vertical partition having its end portions so inclined that the ends of said passages are widened thereby, and having left port formed therethrough at the juncture of the left one of its inclined portions and its uninclined portion, said port opening into the upper one of said outer air passages with its outer or left edge farther than its right edge from said outer back wall; an inner air chamber opening into said ventilated apartment; an air duct one end of which is connected with said vertical partition and communicates through said port with the upper one of said outer air passages the ported end portion of said duct being extended from said partition toward the left end thereof at an incline thereto, said duct being farther extended in a tortuous form and opening into said inner air chamber said duct also being of greater transverse area than the area of said port at its juncture therewith and increasing therefrom in said transverse area to and including its opening into said chamber; and a similarly formed right port for the bottom one of said outer air passages said right port being similarly provided with a reversely arranged air duct and inner air chamber.

6. In a ventilator adapted to ventilate an apartment; an upper horizontally disposed outer air passage having open ends and be-

ing adapted to have air passed and reversely passed therethrough by longitudinal movement and reverse longitudinal movement of said ventilator and by action of the wind 5 blowing and reversely blowing therethrough: a similar lower outer air passage directly beneath said upper passage; an inner wall forming the inner boundaries of both of said passages, said wall having a 10 port formed therethrough opening into said upper passage and a drain opening formed therethrough beneath said port said drain opening and leading into said lower outer air passage; and an air duct communicating 15 with said upper passage through said port and communicating with said lower outer air passage through said drain opening, the walls of said duct being connected with said inner wall at such incline toward the central 20 portion of said outer air passages that air is thereby caused to be admitted through said duct when air is passed through said upper passage and to be exhausted through said duct when air is reversely passed through 25 said upper passage for ventilating said apartment; the whole being adapted to drain and exhaust moisture from said duct.

7. The combination with a ventilator hav-

ing outer air passages and ports therethrough adapted to exhaust and supply air to an apartment; of inner air chambers communicated with said passages said chambers each having an open side opening into said apartment; legs for supporting said ventilator on the sill of a window; a lower inclined plate forming the lower boundary of said open sides of said chambers said plate being extended from said legs and adapted to rest upon said sill for supporting said ventilator and forming a weather tight joint thereunder; an upper inclined plate forming the upper boundary of said open sides of said chambers said plate being adapted to have the sash of an ordinary car window lowered thereon; and a vertical flange on the free edge of said upper plate said flange being adapted to fit against the inner surface of the lower edge portion of said sash for detachably holding said ventilator in position and forming a weather tight joint below said sash.

Corrections in Letters Patent No. 1,104,816.

It is hereby certified that in Letters Patent No. 1,104,816, granted July 28, 1914, upon the application of Chant A. Miller, of St. Louis, and Royal V. Miller, of St. Joseph, Missouri, for an improvement in "Ventilating Devices," errors appear in the printed specification requiring correction as follows: Page 1, line 3, after the comma insert the words *in the county of St. Louis*; page 3, line 101, after the word "having" insert the article *a*; and that the said Letters Patent should be read with these corrections therein that the same may conform to the record of the case in the Patent Office.

Signed and sealed this 15th day of September, A. D., 1914.

[SEAL.]

R. F. WHITEHEAD,
Acting Commissioner of Patents.
